Primary Examiner — Eric Goodman*Assistant Examiner* — Luqman McNeil(74) *Attorney, Agent, or Firm* — Wolf, Greenfield & Sacks, P.C.(57) **CLAIM**

The ornamental design for a surface treatment pad, as shown and described.

DESCRIPTION

FIG. 1 is a bottom plan view of a surface treatment pad showing our new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken lines shown in FIGS. 1-4 and 6 illustrate portions of the surface treatment pad that form no part of the claimed design.

1 Claim, 4 Drawing Sheets(56)
